CLAIM

The ornamental design for a card tray, as shown and described.

DESCRIPTION

FIG. 1 is a perspective view of a card tray of the present invention;

FIG. 2 shows a perspective bottom view thereof;

FIG. 3 shows a top plan view thereof;

FIG. 4 shows a bottom plan view thereof;

FIG. 5 shows a front plan view thereof;

FIG. 6 shows a rear view thereof;

FIG. 7 shows a left side view thereof; and,

FIG. 8 shows a right side view thereof.

The broken lines of the figures showing additional portions of the card tray are included for the purpose of illustrating environmental structure and form no part of the claimed design.
